UNITED STATES PATENT OFFICE.

EMORY E. POSTON, OF CAMPBELL, CALIFORNIA.

CAP FOR INFLATING-VALVES.

1,318,917.

Specification of Letters Patent.

Patented Oct. 14, 1919.

Application filed December 24, 1918. Serial No. 268,153.

To all whom it may concern:

Be it known that I, EMORY E. POSTON, a citizen of the United States, residing at Campbell, in the county of Santa Clara and State of California, have invented certain new and useful Improvements in Caps for Inflating-Valves, of which the following is a specification, reference being had to the accompanying drawings.

10 This invention relates to certain improvements in caps for inflating valves and it is an object of the invention to provide a device of this general character having novel and improved means whereby the same may 15 be readily applied to or removed from operative position and whereby the same, when in applied position is effectively held against accidental displacement.

The invention consists in the details of 20 construction and in the combination and arrangement of the several parts of my improved cap for inflating valves whereby certain important advantages are attained and the device rendered simpler, less expensive 25 and otherwise more convenient and advantageous for use, as will be hereinafter more fully set forth.

The novel features of my invention will 30 hereinafter be definitely claimed.

35 In order that my invention may be the better understood, I will now proceed to describe the same with reference to the accompanying drawing, wherein:

Figure 1 is a view in elevation illustrating 35 a cap constructed in accordance with an embodiment of my invention;

Fig. 2 is a longitudinal sectional view taken through the device as disclosed in Fig. 1 with the valve stem in elevation;

40 Fig. 3 is an elevational view of the improved cap as herein disclosed and substantially the opposite to the elevation shown in Fig. 1, the cap being in position for removal.

Fig. 4 is a sectional view taken substantially on the line 4—4 of Fig. 1.

As disclosed in the accompanying drawings F denotes the felly of a wheel through which extends the hollow stem S of any ordinary or preferred type of inflating valve. 50 In threaded engagement with the stem S inwardly of the felly F is the sleeve or collar 1 which is provided adjacent its outer end with diametrically opposed and oppositely directed outstanding pins 2.

55 C denotes a cylindrical cap having its outer end closed and having its inner end por-

tion enlarged as at 3 to receive the outer end portion of the sleeve or collar 1. The wall of the enlarged portion 3 at diametrically opposed points is provided with the bayonet 60 slots 4 at the free edge of the enlarged portion 3 of the cap C and which is adapted to receive the pins 2 so that upon a partial rotation of the cap C in one direction the cap is held or locked to the sleeve or collar 1. 65

To further assure the retention of the cap C in applied position, I find it of advantage to have slidably engaged within the cap C the block or follower 6 which is constantly urged toward the open end of the cap C 70 through the medium of an expansible member 7 herein disclosed as a conventional coil spring interposed between the block or follower 6 and the closed end of the cap C. The outer face of the block or follower 6 is 75 provided with a compressible insert 8 preferably formed of rubber and which contacts with the outer end of the stem S whereby it will be perceived that the pins 2 will effectively coact with the cap C for maintaining 80 the cap in applied position.

I also find it of advantage to provide a locking member M arcuate in form and having sliding contact with the outer face of the enlarged portion 3 and which member 85 M is held in applied position through the medium of the headed member 9 carried by the enlarged portion 3 and extending through the longitudinally disposed slot 10 formed in the member M. The slot 10 controls the extent of movement of the member 90 M for a purpose which will be hereinafter more fully explained.

An end portion of the member M is provided with a transversely disposed open recess or notch 11 which registers with the longitudinally disposed portion *a* of the bayonet slot 4 when the member M is at the limit of its movement in one direction and said member is of such length as to have its 100 opposite end portion free of the second bayonet slot 4. The recess or notch 11 is of a length equal to the portion *a*, plus the width of the circumferentially disposed portion *b* of the slot 4 so that when a partial rotation 105 is given to the cap C the pins 2 will seat within the circumferentially disposed portions *b* of the slots 4, which is permitted in view of the fact that the slot 10 is of a length substantially equal to the length of 110 each of the portions *b*. The member M outwardly of the recess or notch 11 is provided

with a spring tongue 12 which seats within the portion *a* of the adjacent slot 4 so that the member M effectively holds the cap C against retrograde movement after the same has been partially rotated to effect a locking engagement of the cap with the sleeve or collar 1. It is also to be understood that the end portion of the member M remote from the tongue 12 contacts with the second pin 2 in the circumferential portion *b* of the adjacent slot 4.

From the foregoing description, it is thought to be obvious that a cap for inflating valves constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a valve stem, a collar surrounding said stem and provided with outstanding pins, a cap provided with

an open end, said cap being adapted to be disposed over the stem with its open end portion receiving the collar, said open end portion of the cap being provided with angular slots to receive the pins carried by the collar, and a locking member carried by the cap and adapted to contact with a pin of the collar when the cap is in applied position.

2. In combination with a valve stem, a collar surrounding said stem and provided with outstanding pins, a cap provided with an open end, said cap, being adapted to be disposed over the stem with its open end portion receiving the collar, said open end portion of the cap being provided with angular slots to receive the pins carried by the collar, and a locking member carried by the cap and adapted to contact with the pins of the collar when the cap is in applied position, 45 said locking member being provided with a tongue adapted to seat within a slot of the cap for holding the member against movement in one direction.

In testimony whereof I hereunto affix my 55 signature in the presence of two witnesses.

EMORY E. POSTON.

Witnesses:

JAMES WARREN MCKENZIE,
J. B. STRONG.
